UNITED STATES PATENT OFFICE

124,410

DESIGN FOR A COMBINED WALL ASH TRAY AND SUPPORT THEREFOR

Roy S. Sanford, Oakville, Conn., assignor to The Autoyre Company, Incorporated, Oakville,
Conn., a corporation of Connecticut

Application October 12, 1940, Serial No. 95,796

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Combined Wall Ash Tray and Support Therefor, of which the following is a specification, reference being had to the accompanying drawing, forming a part thereof.

Fig. 1 is a perspective view of the combined wall ash tray and support therefor showing my new design;

Fig. 2 is a front elevational view of Fig. 1; and
Fig. 3 is a side elevational view of Fig. 1.

The dominant features of my new design are shown in full lines and reside in the provision of a vertically extending bracket having a separated ring extending horizontally therefrom and an arm above the ring extending in the same direction.

I claim:

The ornamental design for a combined wall ash tray and support therefor, substantially as shown and described.

ROY S. SANFORD.
